(57) **CLAIM**

The ornamental design for a camera grip with a light, as shown and described.

DESCRIPTION

FIG. 1 is a front perspective view of a camera grip with a light showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a reduced front perspective view thereof, showing the article in use.

The features shown in broken lines in the drawings depict environmental subject matter only and form no part of the claimed design.
